UNITED STATES PATENT OFFICE.

ARNOLD W. PUPKE, OF NEW YORK, N. Y.

MACHINE FOR THE CONTINUOUS MANUFACTURE OF CEMENT AND OTHER TILE OR PIPE.

1,211,230.

Specification of Letters Patent. Patented Jan. 2, 1917.

Application filed September 6, 1916. Serial No. 118,664.

To all whom it may concern:

Be it known that I, ARNOLD W. PUPKE, a citizen of the United States, and a resident of the borough of Manhattan, city, county, and State of New York, have invented a certain new and useful Machine for the Continuous Manufacture of Cement and other Tile or Pipe, of which the following is a specification, reference being had to the accompanying drawings.

Heretofore concrete and similar tile or piping have been made in relatively short sections, usually from two to four feet in length, the smaller the pipe ordinarily the shorter the length of each section, and each section has ordinarily had a so-called bell or socket on one end in which the non-socketed end of the adjoining section entered, thus serving as a means to center and sustain consecutive sections in proper alignment, cement being usually deposited about the joint. These old forms were expensive to manufacture, their weight was increased and consequently the labor and expense of laying them, particularly because of the cement required, was also increased.

It is the purpose of my invention to so construct a machine that the tile or piping will be produced as a continuous unbroken structure of indefinite length and deposited in the bottom of the trench or excavation where it is to remain.

Referring to the drawings, Figure 1 is a plan view of the machine; Fig. 2 is a 35 sidewise elevation of the machine, partly in section, taken on the line 2—2 of Fig. 3, looking in the direction of the arrows; Fig. 3 is a front elevation of the machine; Fig. 4 is a transverse vertical sectional view on the line 4—4 of Fig. 2, looking in the direction of the arrows; Fig. 5 is a longitudinal and diagonal sectional view on the line 5—5 of Fig. 3, looking in the direction of the arrows.

In order that the construction and method of operation of the machine may be more readily understood, it should be stated that the bottom of the trench or other surface upon which the pipe is to be laid, should be prepared and graded prior to the use of the machine. A suitably constructed track, which may beneficially be made of ordinary two by four studding nailed together on the break joint principle, should then be laid in the bottom of the trench or upon the surface which is to receive the pipe, and along

this track the machine about to be described will move during the making and laying of the pipe.

Referring to the drawings, 1 is a rectangular frame upon which the apparatus is supported. It may be made of any preferred material, preferably angle iron as shown, and in any preferred manner.

2, 2, are a series of rollers, preferably in the form of flanged wheels, as shown, upon which the apparatus is supported and moved upon the tracks 3, 3, (see best Fig. 3) which, as stated above, are laid in the bottom of the trench or upon the surface on which the pipe is to be laid.

4 is what may be called a plowshare excavator. It is made rounding on its forward edge as shown best in Fig. 3, and has a downwardly extending point or forward end 5, as best seen in Figs. 1 and 2. As the plowshare extends rearwardly it expands to the right and left and rolls over outwardly after the fashion of a railway snow plow, forming mold boards 6, 6, adapted to spread to the right and left the earth excavated by the forward part of the plowshare.

At the rear of the machine and suitably supported upon the frame are what may be called reverse mold boards 7, 7, which are so located, shaped and set at such an angle as to draw inwardly again and deposit against the rear part of the cement chamber, hereinafter to be described, this material, so that as the machine advances it will be deposited about and upon the newly made pipe.

8 is a shaft supported upon bearings 9, 9, upon which is a grooved wheel 10.

11 is a bevel gear fastened to the side of the grooved wheel 10 which drives the beveled pinion 12 mounted upon a counter-shaft 13 supported in bearings 14, 14, best seen in Figs. 1 and 2, upon which is a pinion 15, which meshes into another pinion 16, which is mounted upon a hollow shaft 17 (see Fig. 5) which runs longitudinally through the machine, passing through the compartments 18 and 19. Upon the shaft 105 and within the compartments is a worm feed 20. The forward end of the compartment 19 is partly open as at 21, see Fig. 5, and the rear end of the compartment 19 is entirely open. On a part of the outer periphery of the worm feed 20 is a cylindrical shield 22, which forms one wall of an an-

nular chamber 22', its other wall being the outer wall 19' of the compartment 19, and in this annular chamber 22' is a supplemental worm feed 23, which is connected 5 with the shaft 17 in any suitable manner and is driven by it.

Above the compartment 18 is a hopper 24 and above the compartment 19 is another hopper 24'. For convenience these hoppers 10 may be built as a single structure and divided by a partition 24². In these hoppers respectively are what may be called rotary strippers 25 and 26. They are peculiarly shaped devices best seen in Fig. 5, and are 15 in effect solid disks, each having a series of radial slots, as shown, in which slots the worms engage respectively, so that should there be any tendency on the part of the material either to adhere to the worms or 20 to revolve with the worm shaft, in either event failing to feed longitudinally, then these strippers will not only prevent revolution of the material with the shaft, but will also remove from the worms any part 25 of the material which adheres thereto, and thus the material will be compelled to feed longitudinally under the action of the worms. Each of these strippers is mounted upon a suitable supporting axis or center 27. 30 (see Figs. 2 and 5) is a wire, cord, or, if preferred, a rubber hose, which is fed from a reel placed in advance of the machine and passes through the hollow shaft 17 and is deposited in or near the center of 35 the core for the pipe as it is being laid.

The operation of the machine is as follows: The trench or excavation having been made and the track laid therein or thereon as above described, the machine is placed 40 preferably at an end of the line of pipe to be made. Core-making material, preferably sand, which has been screened, although suitable earth or equivalent material may be used, is deposited in the compartment 18 45 through its hopper 24, and sand, preferably screened, mixed with a suitable proportion of cement and water, as is well known, is deposited in the compartment 19 through its hopper 24'. It will be noted that the material 50 in the compartment 18 will entirely surround and cover that portion of the worm 20 which is within the compartment and will also solidly fill that part of the compartment 19 which is within the shield 22, 55 and that the sand, cement and water will entirely fill the annular chamber 22'. The wire, rope or hose 28, as the case may be, is unrolled from its reel and is passed through the hollow shaft 17, as indicated 60 best in Fig. 5, and its end is made fast to some suitable anchorage. One end of a draft rope or cable, not shown, is attached to a suitable anchorage in advance of the machine and distant therefrom as far as desired, the free end of which is passed around

the grooved wheel 10 and carried back again to a suitable source of power, which may be a windlass, a motor, a tread mill or the like. The power being now started, the machine, under the action of the draft line, will move 70 along the track; the plowshare will cut a semi-cylindrical groove or bed for the pipe in the surface along which the pipe is to be laid; the front mold boards of the plowshare will remove the excavated material to the right and left, depositing it by the side of the advancing machine, and it cannot fall back again into the excavation made by the plowshare, because the lower exterior surface of the body of the machine, shown 75 best at 19', in Fig. 4, which extends rearwardly to the point where the pipe forming cement is projected from the machine, will rest always in the bed cut by the plow and maintain its contour, and smooth and compact its surface. The traction of the line over the grooved pulley 10 will powerfully 80 rotate it, and thus drive the chain of gearing described, rotating the hollow worm shaft 17 and the feeding worms 20 and 23 85 attached to it, so that the worm 20 will continually discharge from the rear of the machine a core of sand or other material and the worm 23 will continually discharge from the rear of the machine a hollow cylindrical 90 body of plastic cement, which will surround and be supported by the core ejected by the worm 20. As the plastic cement body is delivered at the rear of the machine, the mold boards 7, 7, which, as stated, are located at 95 the rear end of the machine, will draw the material excavated by the plowshare and moved laterally by the front mold boards 6, inwardly against the upper half of the outer wall 19' of the chamber 22', so that as 100 the machine advances, this material will be deposited about and upon the upper half of the newly made pipe. Thus the pipe will be sustained throughout its lower half by the bed made for it by the machine, on 105 its upper half by the material deposited upon it as stated, and by the core interiorly, until it is sufficiently set or hardened to be self-sustaining, after which it will of course 110 additionally harden and, as is well known, 115 become monolithic. As the machine advances, the rope, wire or hose 28, as the case may be, will be unreeled and deposited in about the center of the core, thus forming a continuous removable device extending 120 longitudinally through the center of the core, so that after the pipe making operations are completed, and the pipe sufficiently 125 solidified to permit the removal of the core, this rope, wire, or hose may be moved longitudinally back and forth through the length of the pipe, thus loosening the core material and removing it little by little, until a passage to receive water under pressure is made, whereupon the material may be 130

readily washed out. If this device be a rubber hose, which I prefer, then upon the completion of the pipe forming operation, it may be pulled forwardly a few feet at a time and water under pressure forced through it, so that the core material will be completely washed out in a step by step manner as the hose is step by step withdrawn.

It will be noted that there must be a certain relation between the feed of the core making material and the mixed sand, cement and water by the worms and the forward speed or movement of the machine, so that there will never be any failure on the part of the machine to get out of the way of the pipe formation, for if it does not advance with substantially the same speed as the pipe is made, then the cement and core material being continually ejected would pile up in rear of the machine in a shapeless mass or accumulation. Also I prefer to so time the operation of the parts involved that the cement shall be ejected under sufficient pressure to compensate for the thickness of the shells 19' and 22. This is purely a matter of adjustment of the mechanism which any competent engineer or contractor will at once perceive.

It will also be noted that the track may be of such length as desired. After the completion of one section of pipe, it may be taken up and transferred to the next section in advance of the machine and thus be used indefinitely.

In the event that the length of pipe shall be such that it would be difficult to start the wire, rubber hose or other core-removing device, owing to the frictional holding thereof, then I sometimes make an opening in the pipe, say every 50 or 100 feet, more or less, depending upon the circumstances, through which the core removing device, whatever it may be, may be gotten hold of and removed sectionally, so to speak. Such opening may be small, resembling an ordinary man-hole, or a portion of the pipe may be removed for a distance equal preferably to the length of an ordinary tile of the same diameter, so that after the removal of the core, any such break in the continuity of the pipe can be quickly and inexpensively repaired by setting in a section of tile of the proper diameter and suitably embedding and incasing it in cement.

It will be noted that the machine above described and illustrated is one form only of many in which my invention may be embodied and that modifications may be made therein without departing from the essentials of the invention. For example, it may not always be necessary to employ a track. Skids or runners under certain circumstances may be employed instead of the rollers or flanged wheels. Also other means of ad-

vancing the apparatus and those described may be employed. Indeed the apparatus may be modified in various respects. I therefore do not limit myself to the details above described and illustrated.

70

I claim:

1. A machine of the class stated embodying an excavating device at its forward end, a chamber for granular core making material, a separate chamber for plastic material, such as mixed cement, means carried by the machine to simultaneously eject from the rear thereof and deposit a central core of the granular material and a body of the plastic material surrounding the core and means to advance the machine.

2. A machine of the class stated embodying a device at its forward end adapted to excavate a groove or bed conforming to the exterior shape of a portion of the pipe, a chamber for granular core making material, a separate chamber for plastic material, such as mixed cement, means to simultaneously eject from the rear of the machine and deposit a central core of the granular material and a body of the plastic material surrounding the core, and means to advance the machine.

3. A machine of the class stated embodying a device at its forward end adapted to excavate a groove or bed conforming to the exterior shape of a portion of the pipe, an underbody part of the machine adapted to move along the said excavated groove or bed and smooth and press its exterior surface, a chamber for granular core making material, a separate chamber for plastic material, such as mixed cement, means to simultaneously eject from the rear of the machine and deposit a central core of the granular material and a body of the plastic material surrounding the core, and means to advance the machine.

4. A machine of the class stated having an excavating device at its forward end provided with means to deliver the excavated material laterally, means carried by the machine for simultaneously ejecting from its rear end a central core of removable granular material and an exterior body of plastic material, such as cement, surrounding the core, and means adjacent to the delivery end of the machine for moving the excavated material inwardly about and upon the body of plastic material.

5. A machine of the class stated having an excavating device at its forward end provided with means to deliver the excavated material laterally, means carried by the machine for simultaneously ejecting from its rear end a central core of removable material, a continuous device adapted to longitudinal removal embedded in the central core, an exterior body of plastic material, such as mixed cement, surrounding the core,

120

125

130

and means adjacent to the delivery end of the machine for moving the excavated material inwardly about and upon the body of plastic material.

5 6. A machine of the class stated having a power driven shaft extending through a chamber adapted to contain core making material, a worm feed in said chamber driven by the shaft, a chamber adapted to 10 contain plastic material, such as mixed cement, surrounding a portion of the first named chamber, and a worm therein rotated by the driven shaft, both of said chambers terminating on substantially the same vertical line.

7. A machine of the class stated having a wheel at one end over which a draft device passes, gearing connecting said wheel with a longitudinally extending shaft, chambers in the machine for the reception of core making material and plastic material, such as mixed cement, through which chambers the shaft passes, and feeding devices actuated by the shaft in both chambers 25 whereby core making material will be ejected from one of the chambers and simultaneously therewith plastic pipe making material surrounding the core making material from the other of said chambers.

30 8. A machine of the class stated having a wheel at one end over which a draft device passes, gearing connecting said wheel with a longitudinally extending shaft, chambers in the machine for the reception respectively of core making material and plastic material, such as mixed cement, through which chambers the shaft passes, feeding devices actuated by the shaft in both chambers whereby core making material will be ejected from one of the chambers and simultaneously therewith plastic pipe making material surrounding the core making material from the other of said chambers, and a longitudinally removable 45 device deposited within the core making material as the work progresses.

9. In a pipe making machine, compartments to contain respectively core making material and plastic material, such as mixed cement, means to simultaneously discharge from the rear of the machine the core making material and the pipe making plastic material surrounding the same, and means to continuously feed and deposit within the core making material a longitudinally movable device for subsequently removing the core.

10. In a machine of the class stated, means at one end of the machine for excavating a

channel or bed for the pipe and for moving the material so excavated laterally, other means at or near the rear end of the machine for drawing the said excavated material inwardly, means interposed between the two parts for simultaneously projecting from the rear of the machine a central core of suitable material surrounded by a pipe of plastic material, such as mixed cement, means to continuously deposit within the core as the work progresses a longitudinally movable device adapted to aid in the subsequent removal of the core and means to advance the machine which also afford the power for the rearward ejection of the core and pipe making materials. 75

11. In a machine of the class stated, a power driven shaft provided with worm feeds rotating in separate spaces or chambers, one adapted to contain core making material and the other pipe making plastic material, such as mixed cement, and rotatable disks to insure longitudinal feed of the material.

12. In a machine of the class stated, an excavating device at the forward end adapted to cut a channel or bed for the pipe, means to move the material so excavated laterally, chambers or spaces in the body of the machine, one adapted to contain core making material and the other pipe making plastic material, such as mixed cement, a shaft provided with worm feeds working in each of said chambers for the rearward ejection of the material contained in them respectively and a traction device in advance of the machine whereby it is advanced and the shaft and worm feed actuated. 85

13. In a machine of the class stated, an excavating device at the forward end adapted to cut a channel or bed for the pipe, means to move the material so excavated laterally, chambers or spaces in the body of the machine, one adapted to contain core making material and the other pipe making plastic material, such as mixed cement, a shaft provided with worm feeds working in each of said chambers for the rearward ejection of the materials contained in them, a traction device in advance of the machine, whereby it is advanced and the shaft and worm feed actuated, and means to continuously deposit through the core a longitudinally removable device whereby the core may be removed. 100

In testimony whereof I have signed my name to this specification. 115

ARNOLD W. PUPKE.
